UNITED STATES PATENT OFFICE.

WILLIAM J. BEISEL, OF BROOKLYN, NEW YORK.

SPINNING-MACHINE.

1,264,599.

Specification of Letters Patent. Patented Apr. 30, 1918.

Application filed January 5, 1916. Serial No. 70,471.

To all whom it may concern:

Be it known that I, WILLIAM J. BEISEL, a citizen of the United States, and resident of Brooklyn, Kings county, State of New York, 5 have invented certain new and useful Improvements in Spinning-Machines, of which the following is a specification.

My invention relates to spinning machines and has particular reference to a machine 10 suitable for spinning grooves or beads on cylindrical bodies. The machine is especially suitable for spinning grooves in the necks of bottles such as are shown in my Patent No. 1,144,287 of June 22, 1915, and 15 for securing or spinning on the collars of such bottles.

The principal object of my invention is to provide a simple machine of this character which is efficient and easily manipulated.

20 The above and further objects and the novel features of the invention will be apparent from the following description taken in connection with the drawing, in which:—

Figure 1 is a side elevation of a spinning machine embodying my invention, parts thereof being shown in section;

25 Figs. 2 and 3 are respectively an enlarged detail, and an enlarged cross section on the line 3—3 of Fig. 2, showing the construction 30 of the spinning jaws;

Fig. 4 is a horizontal sectional view on the line 4—4 of Fig. 1;

Fig. 5 is a detail sectional view on the line 5—5 of Fig. 1; and

35 Fig. 6 is a top view of the pivotal support for the spinning arms.

Referring to the drawing, the reference numeral 10 designates a vertical portion of the machine frame, being mounted on a base 40 11 and provided with an overhanging part 12 at the upper end having two laterally extending bearing portions 13 and 14.

The bottle B upon which the grooves are to be spun or the collar C is to be secured is 45 supported in a recess in the top face of the chuck member 15 which slides up and down in an opening 16 in the top part of the base 11. The upper end of the bottle fits into the opening 17 of a stationary chuck member 18 50 which latter is axially in line with the movable chuck member 15 which engages the bottom of the bottle. An adjustable nut 19 is secured in the top of the opening 17 to engage the cork of the bottle to press it 55 into the mouth of the bottle. The stationary chuck 18 is fixedly secured as by a pin to

the lower end of a cylindrical rod 20 which extends upwardly through the bearings 13 and 14 and is keyed against rotation by a key 21 in the bearing 14. 60

A pair of spinning arms 22 and 23 are mounted on opposite sides of the rod 20, being pivoted as at 24 and 25 to the opposite arms 26 of a spinning arm support 27. The spinning arm support 27 is connected by a 65 tube 28 to a bevel gear 29. The tube 28 is threaded into the support 27 and the gear 29 and surrounds the rod 20 and turns independently of the latter. The spinning arms 22 and 23 are therefore carried by the 70 gear 29.

The ends of the arms 22 and 23 below the pivots 24 and 25 respectively carry the spinning devices, which are similar in all respects and only one of these devices will 75 therefore be described.

A portion of each spinning arm is of such a length that it terminates opposite that portion of the bottle in which the grooves are to be spun or upon which the collar C is to be secured. 80

The lower end of each of the spinning arms has an inclined face 30 to which the jaws 31 of the spinning devices are secured by bolts 32.

It will be understood of course that the jaws 31 might be made integral 85 with the arms 22 and 23. The outer faces 33 of the jaws 31 are curved and shaped so as to conform to the shape to which the collar or the neck is intended to be spun.

Each jaw has two vertically spaced 90 recesses 34 and 35 which open at the face 33, leaving spinning faces 331 between the recesses and spinning faces 332 below the recesses.

The faces between and on opposite sides of the rollers 36 are curved to fit 95 the collar C and will smooth the parts of the collar adjacent the grooves formed by the rollers 36.

A pair of rollers 36 is located in each of the recesses 34 and 35 and the rollers 36 project beyond the face 33 100 a slight amount in order to provide for spinning the grooves.

A bolt 37 passes through portions of the jaw member 31 and transversely through the recesses 34 and 35. The bolts 37 also extend through the 105 rollers 36 in the recesses 34 and 35, so as to hold the rollers 36 in place and provide

shafts upon which they may rotate. The spinning dies including the jaw members 31 and rollers 36 are preferably of tool 110 steel to provide for long wear. When the spinning dies are in spinning position they

are in line with one another and the line joining the center of the rollers passes through the axis of the cylindrical rod about which the dies rotate. It will be seen that the jaws may be readily detached and renewed when desired without taking the arms down. The arms 22 and 23 have portions 39 and 40 which extend above the pivots 24 and 25 and are provided with oppositely disposed cam surfaces 41 and 42 which are inclined downwardly and inwardly toward the axis of the rod 20. The extreme upper ends of the parts 39 and 40 are disposed in recesses 43 in the under side of the bevel gear 29 and are provided with transverse slots 44 to receive the pins 45 whereby they are secured to the gear 29 to rotate therewith. The slots 44 allow a small amount of movement of the arms 22 and 23, sufficient to throw the extreme lower ends thereof and the rollers thereon into engagement with the bottle or other article to be spun. The lower ends of the arms 22 and 23 with the jaws and rollers are normally held spaced apart by springs 46 located above the pivots 24 and 25 and attached to each side of the arms 22 and 23.

The lower ends of the arms 22 and 23 may be pressed inwardly by means of a curved lever 47 pivoted at 48 and connected by a link 49 to the arm 50 of a cam operating fork 51. The members 50 and 51 move together and are pivoted at 52 on the frame member 10. The cam fork 51 has arms which extend into the outer groove 53 of a circular cam member 54. The cam member 54 has a central opening 55 to fit the exterior of the tube member 28 and is adapted to slide along the latter. On opposite sides of its center the cam member 54 also has openings 56 and 57 to receive the outer ends 39 and 40 of the spinning arms 22 and 23. Cam projections 41 and 42 on the arms 39 and 40 are engaged by correspondingly inclined surfaces in the openings 56 and 57 and it will be readily seen that when the cam 54 is moved downwardly the arms will be pressed outwardly and thereby press the parts of the arms 22 and 23 below the pivots inwardly toward the container B. The springs 46 hold the co-operating cam surfaces on the cam 54 and the members 39 and 40 in contact so that the operation of the cam will cause a corresponding operation of the spinning arms.

The upper side of the gear 29 has a boss 291 which is long enough to project upwardly through the bearing 13 and has a flange 292 to retain the gear 29 in position in the bearing 13. The gear 29 is driven by a meshing bevel gear 60 mounted on the same shaft with the pulley 61 which is driven by a belt 62 from the loose pulley 63 carried by the shaft 64. The shaft 64 has one end mounted in the base 11 and

the other end is mounted in the outer bearing 65 of the frame member 10 and is driven by a pulley or other suitable driving means 66. The loose pulley 63 rotates with the shaft 64 when the clutch member 67 is in engagement with the wheel 63. The clutch member 67 is splined on the shaft 64 and has a grooved boss carrying a collar 68. A link 69 is connected to the collar 68 and shifts the clutch member 67 into and out of contact with the loose pulley 63. The link 69 is operated by means of a foot lever 70 pivoted at 71 and provided with an arm 72 to which the link 69 is pivoted. The foot lever 70 also carries a roller 73 which engages the lower end of a rod 74 connected to the chuck member 15. The distance between the chuck members 15 and 18 may be varied to take bottles of different sizes.

The operation of the device will be apparent from the foregoing description. When the bottle B has been set on the chuck member 15, the latter is raised by depressing the foot lever 70. This moves the bottle upwardly until the upper end of the neck thereof fits into the stationary clutch member 18, and simultaneously with this movement the clutch member 67 is thrown into engagement with the pulley 63. This starts the rotation of the gear 29 and the spinning arms connected therewith. The lower ends of the spinning arms can then be gradually closed or moved inwardly by depressing the lever 47 and moved outwardly when desired by raising the lever 47.

While I have shown and described the construction in detail I do not wish to be limited to the precise forms or arrangements as it is obvious that various changes may be made therein without departing from the spirit of the invention.

Having described the invention what is claimed is:

1. In a machine for simultaneously forming parallel rings on a container or a part thereof, the combination of a support for a container, a spinning device having faces adapted to engage said container or a part thereof and rollers on opposite sides of one of said faces for engaging said container or a part thereof, means for rotating the spinning device and container relatively to and in engagement with each other whereby parallel rings are simultaneously formed on the container or part thereof.

2. In a machine of the class described, the combination of a frame having an overhanging part, a stationary vertical shaft mounted in said overhanging part, a chuck fixed on the lower end of said shaft, a vertically adjustable chuck co-operating with said fixed chuck, a gear rotatable about said shaft, a spinning arm support connected to said gear and rotatable therewith around said shaft, spinning arms pivoted on said

support, spinning devices carried by said arms, operating means, means for simultaneously raising the adjustable chuck and connecting the operating means to said gear 5 to rotate the latter and the spinning devices, and means for moving the spinning devices toward and away from the container held by said chucks.

3. In a machine of the class described, 10 the combination of a pair of non-rotatable chucks mounted axially in line on a vertical axis and adapted to hold a container between them, a gear rotatable about said vertical axis, a spinning arm support carried by said gear and rotatable therewith, spinning arms pivoted intermediate their ends on said support, spinning rollers mounted on the lower ends of said arms, a cam ring between said gear and support and 15 rotatable therewith but also movable along said vertical axis, said ring having openings therein to receive the upper ends of said arms and adapted to rock said arms on their pivots to move the lower ends thereof and 20 the spinning rollers thereon toward and from a container held by said chucks, means for driving the gear and parts connected therewith, means for controlling the connection of the driving means to the gear and 25 also for controlling the movement of the lower chuck, and means for controlling the movements of said cam ring.

4. In a spinning machine, the combination of a bottle support comprising two axially mounted chucks adapted to engage the ends of the bottle, one of said chucks being fixed and the other being movable, a pair of arms

pivotedly mounted intermediate their ends, spinning devices on the lower ends of said arms, means for normally holding the spinning devices away from the bottle on said support, means for pressing the arms and spinning devices thereon against the bottle on said support, a gear above the pivots of said arms and connected to the upper ends 45 of said arms, means for rotating said gear and means for controlling said rotating means and the movable chuck.

5. In a spinning machine for simultaneously forming two or more parallel rings 50 on containers or parts thereof, a jaw member having spaced recesses in the working face thereof, rollers mounted in said recesses and a pin in said jaw passing transversely through the recesses and the rollers 55 to hold the latter in place and constituting a shaft therefor.

6. In a machine for simultaneously forming two or more parallel circumferential rings about the neck of a bottle, the combination of a bottle support, a pivoted arm rotatable around the axis of a bottle on said support, a plurality of vertically spaced rollers mounted on the lower end of said arm, means for pressing the lower end of 60 said arm and the rollers thereon inwardly against the neck of a bottle on said support, and means for rotating said arm to simultaneously form vertically spaced parallel rings about the neck of a bottle on the 65 support.

In testimony whereof I affix my signature.

WILLIAM J. BEISEL.
